AUTOMATIC SIGNAL OPERATING DEVICE FOR MAIL BOXES

Filed Feb. 21, 1922

2 Sheets-Sheet 2

Fig. 4.

UNITED STATES PATENT OFFICE.

HERMAN C. FEIST, OF ROWENA, TEXAS.

AUTOMATIC SIGNAL-OPERATING DEVICE FOR MAIL BOXES.

Application filed February 21, 1922. Serial No. 538,295.

To all whom it may concern:

Be it known that I, HERMAN C. FEIST, a citizen of the United States, residing at Rowena, in the county of Runnels and State 5 of Texas, have invented certain new and useful Improvements in Automatic Signal-Operating Devices for Mail Boxes, of which the following is a specification.

My invention relates to rural delivery 10 mail boxes and has for its main object to provide automatic means for raising a flag directly mail has been deposited in the box, thereby signaling to the owner that mail is awaiting him, or to the mail carrier that he 15 should empty the box.

The device is a time saver in that the person emptying the box has no additional 20 operation to perform for giving the signal beyond that of opening and closing the door on the mail box. This has also the advantage that the setting of the signal does not 25 directly depend on his actions, but is performed by him unconsciously in opening and closing the box and cannot for that reason be forgotten.

Another advantage of the invention is that it constitutes an accessory to a mail box so that it may be as easily inserted in an old box as in a new one.

The device is, moreover, so simple and 30 consists of so few and substantial parts that it cannot get out of order from daily use.

One embodiment of the invention is illustrated in the accompanying drawings, 35 where

Figure 1 represents a rural delivery mail box of the usual design and with my improvement attached as shown in perspective view;

Figure 2 is a transverse section of the mail 40 box on a larger scale;

Figure 3 is a perspective view of an insert containing the details constituting the invention;

Figure 4 is another perspective view of 45 the details separated.

In the drawings, the reference numeral 10 represents a rural delivery mail box provided with a door 11 hinged to the fixed 50 bottom 12 of the same. Upon this door is secured an inwardly projecting finger 13, preferably constructed of a thin metal plate with the high dimension in the vertical direction and terminating with a dovetail portion 14. This projecting finger 13 is so posi-

tioned that it extends inwardly a short distance in the box 10 when the door 11 is closed.

The device constituting the invention is constructed as an insert with a long narrow 60 base 15 approximately of the same dimensions as the fixed bottom 12 of the box so that the base 15 may be positioned upon the bottom of the box and no part thereof extending outside of the latter. This base 15 has preferably a flanged bar 16 riveted along one side thereof with an upright bearing piece 17 nearer the inner than the outer end of the base. In this bearing piece 17, a spindle 18 is mounted to rotate and on the spindle 65 is rigidly secured an arm 19 adapted to swing about 90° as limited by the upper stop 20 and the lower stop 21 attached to the outer side of the box 10. An upright wall 22 is formed by bending over one side of the 70 base 15. This upright wall also forms a bearing for the spindle 18.

On the shaft 18 is also secured a lever 23 provided with a stud 24 engaging in the 75 looped end 25 of an operating rod 26, which terminates with a flat dovetailed portion 27. This tail portion 27 is placed with its wider dimension in an approximately horizontal plane.

Slightly raised above the base 15 is shown 80 a false bottom 28, which is secured on a transverse shaft 29 pivoted at 30 in the base 15 and provided with washers 39 to prevent rubbing of the bottom 28 against the sides. This arrangement will permit of a slight 85 oscillation of the false bottom with the shaft 29 with regard to the base. The position of the shaft 29 beneath the false bottom 28 has been selected so that the outer portion of the false bottom, near the door of the box, is approximately twice or three times the length 90 of the inner portion of the false bottom. At the inner edge of the false bottom 28 is secured a weight 31 which is intended to give a slight preponderance at the inner end 95 of the false bottom so that, when free, the inner end of the bottom 28 will rest upon the base 15 and as a consequence the outer end 32 of the false bottom 28 will be raised above the base 15, as best seen at 33 in 100 Figure 1. The preponderance caused by the weight 31 is not greater than will be overcome by the placing of a very light object at the outer end 32 of the false bottom so that, for instance, if a postal card were deposited 105 110

on this end, the false bottom would be tilted and the outer end 32 would strike and rest upon the base 15 and remain in this position as long as this object stayed on the false 5 bottom.

Rigidly secured on the shaft 29 or forming an integral part thereof is a lever 34, which extends in the direction toward the door of the box and is bent upwardly so that 10 its forked end 35 is able to embrace the rod 26, and a pin 36 or other suitable means is provided to close the opening in the fork to prevent the rod from jumping out during the operation.

15 The function of this lever 34 is now to position the tail 27 of the rod 26 so that the tail will be in the path of the dovetailed portion 14 of the finger 13, when the door 11 is being closed and when the false bottom 20 28 is tilted, with its outer end 32 resting upon the base 15. In other words, as soon as a piece of mail is dropped in the box and the door is closed, the finger 13 will engage with the tail 27 on the rod 26, which has 25 such a length that the tail will stand about even with the perpendicular outer end of the side wall of the mail box. When the door is completely closed, the finger 13 will push upon the tail 27 and drive the rod 26 inward, whereupon the latter will swing the lever 28 as well as the spindle 18 and the arm 19 carrying the flag 37 secured on the outer end thereof. In this manner, the flag 37 will be raised and the action of the rod 26 limited 30 by the striking of the arm 19 against the stop 20.

When subsequently the door 11 is opened for the purpose of emptying the mail box, 40 the flag will immediately fall when the pressure of the finger 13 against the tail 27 is released upon the swinging of the door. Directly the mail has been removed from the false bottom 28, the outer end 32 will be lifted by the weight 31, which has as a consequence 45 the lifting of the lever 34 and the rod 26. Should no mail be deposited in the box at this time, the outer end 32 of the false bottom 28 will remain in its upper position and consequently the tail 27 will stand above the 50 finger 13 when the door is being closed. As no engagement between the finger 13 and tail 27 can now take place, the arm 19 and the spindle 18 will remain inactive and the flag 37 will stay in its lowered position, as seen 55 in Figure 1.

It will be evident that this device may very easily be applied to existing mail boxes and that all that will be required is to secure the finger 13 on the door and the stops 20, 60 21 on the box and attach the flag 37 upon the outer end of the spindle 18, and that for this purpose a small hole is to be drilled in the side of the mail box.

In new mail boxes, on the other hand, the

base 15 may be dispensed with altogether 65 and the moving parts attached directly in the box itself.

I reserve the right of making minor changes in the construction within the scope of this specification and claims, as for instance leaving out lever 34 and securing the fork 35 directly on the false bottom 28 by means of an upwardly directed arm. In such a case it is evident that a slot will have 70 to be provided in the upright wall 22 for the arm to work up and down in, when the false bottom 28 oscillates.

Having thus described the invention, what is claimed as new is:

1. The combination with a mail box having a swinging door; of a signal member, a spindle for said signal member pivoted in the box and keyed to the signal member, an arm rigidly attached to said spindle, and means inserted between said door and said arm for operating the signal member through the swinging of said door, said means including a rod pivoted on said arm, a projection on said door adapted to engage with said rod when the door is closed, a false bottom in said box, a shaft upon which the false bottom is secured, a lever rigidly connected with said shaft, said lever having sliding engagement with said rod, said false bottom having a slight preponderance at 90 the end away from said door, whereby said false bottom in co-operation with said lever is adapted to position said rod in the path of said projection upon the swinging of said door, when said bottom is being actuated by the depositing of a light object thereupon adjacent to the door.

2. The combination with a mail box having a swinging door; of a signal member, a spindle for said signal member pivoted in the box and keyed to the signal member, an arm rigidly attached to said spindle, and means inserted between said door and said arm for operating the signal member through the swinging of said door, said means including a rod pivoted on said arm, a projection on said door adapted to engage with said rod when the door is closed, a false bottom in said box, a shaft upon which the false bottom is secured, an element rigidly connected with said bottom, said element having sliding engagement with said rod, said false bottom having a slight preponderance at the end away from said door, whereby said false bottom in co-operation with said element is adapted to position said rod in the path of said projection upon the swinging of said door, when said bottom is being actuated by the depositing of a light object thereupon adjacent to the door.

In testimony whereof I affix my signature.

HERMAN C. FEIST. [L.S.]
